G. H. VAN NOY
ELECTRIC WATER HEATER

Filed Feb. 13, 1922

UNITED STATES PATENT OFFICE.

GEORGE H. VAN NOY, OF LEWISTOWN, MONTANA.

ELECTRIC WATER HEATER.

Application filed February 13, 1922. Serial No. 536,166.

To all whom it may concern:

Be it known that I, GEORGE H. VAN NOY, a citizen of the United States, residing at Lewistown, in the county of Fergus and 5 State of Montana, have invented a new and useful Electric Water Heater, of which the following is a specification.

This invention relates to an electric water heating attachment for domestic boilers, one 10 of its objects being to provide means whereby without changing the circulation of water within a domestic boiler or providing any extra taps in the boiler, the water contained in said boiler can be quickly 15 heated electrically by applying to said boiler an electrode of novel construction.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention 25 shown can be made without departing from the spirit of the invention.

In the accompanying drawings the preferred form of the invention has been shown.

30 In said drawings—

Figure 1 is a longitudinal section through the electrode or attachment constituting the present invention.

Figure 2 is a section through a domestic 35 boiler showing the present improvements combined therewith.

Referring to the figures by characters of reference 1 designates a tubular body of 40 metal provided with a radial branch or extension 2 which is interiorly screw threaded and is located between the ends of the body. One end of the tubular body can be enlarged and made angular as at 3 so as to be properly engaged and rotated by a wrench while 45 the other end of the body can be screw threaded as shown at 4 whereby said body can be screwed into the opening 5 usually provided in the bottom of a domestic boiler 6 and to which the outflow pipe of a domestic 50 water system is ordinarily connected.

Seated within that portion of the body 1 between the branch 2 and the enlarged end 3 is a core 7 of porcelain or other suitable insulating material, one end of this core 55 being preferably formed with an annular flange 8 for lapping the end of the body as

shown in Figure 1. A tubular stem 9 of porcelain or other insulating material is extended from the inner end of the core 7, this stem projecting past the branch 2 and 60 beyond the threaded end 4 of the body. A bore or passage 10 is extended longitudinally through the core and its stem 9 seated within this bore or passage is a metal rod 11 which constitutes one electrode of the 65 heating apparatus. That end of the rod projecting beyond the flanged end of the core 7 has a recess 12 for the reception of a wire terminal 13, there being set screws 14 for fastening the terminal in place. 70 That portion of the rod which projects beyond the stem 9 is slightly enlarged in diameter as shown at 15 and can be of any length desired. A shoulder 16 is provided at the lower end of this enlarged portion 75 and bears against the end of the stem 9.

The rod is adapted to extend parallel with and at a short distance from the water feed pipe 17 which extends downwardly into the boiler 6 from the top thereof. The 80 other wire terminal 18 is attached to this pipe 17 as shown in Figure 2. Thus it will be seen that when a current of electricity is directed to the rod 11 and the pipe 17 there will be a discharge from one to the other 85 through that portion of the water interposed therebetween with the result that the temperature of the water will be quickly raised. An outlet pipe not shown can be connected to the branch 2 so that heated 90 water can be drawn from the boiler through the space between the body and the stem 9, as will be obvious.

By increasing or reducing the length of the rod 11 the time required to heat the 95 water can be increased or reduced.

What is claimed is:—

1. An electric water heating attachment for domestic boilers including a tubular body insertible into the water outlet opening in the boiler, a core of insulating material filling one end portion of the body, and a rod of conductive material extending through the core and adapted to lie close to and parallel with the water feed pipe in 100 a boiler, said rod and feed pipe being connected to opposite terminals of an electric circuit.

2. An electric water heating attachment for domestic boilers and the like including 110 a tubular body for insertion into the outlet opening of the boiler, said body having

a branch outlet for water, a core of insulating material filling one end portion of the body, a tubular stem projecting from the core and formed of insulating material, said 5 stem being spaced from the body to provide a water passage around the stem and leading from one end of the body to the outlet in the body, and an electrode extending longitudinally through the core and stem 10 and beyond said stem, said electrode being adapted to be supported close to and parallel with the water feed pipe in a boiler, said pipe and electrode being adapted to be connected to opposed terminals of an electric 15 circuit.

3. The combination with a domestic boiler or the like having a feed water pipe extending thereinto and connected to one terminal of an electric circuit, of an attachment 20 including a tubular body insertible into the outlet opening of the boiler and having a water outlet, a core of insulating material closing the outer end of said body and extending close to the outlet, a stem of 25 insulating material projecting from the core and into the boiler from the body, said stem being spaced from the body to provide a

water passage leading to the outlet, and an electrode extending through the core and stem and close to and parallel with the 30 pipe, said electrode being connected to the other terminal of the electric circuit.

4. The combination with a water container and a water feed pipe supported therein, of a tubular body detachably engaging and opening into the container, there being a lateral water outlet in the body, an insulating core closing the outer end of the body, there being a tubular insulating stem projecting to and beyond the open end of 40 the body and into the container, an electrode extending through the core and stem and supported by the stem, said electrode being disposed close to and parallel with the water feed pipe said electrode and the water 45 feed pipe being electrically connected to the opposed terminals of an electric circuit.

In testimony that I claim the foregoing as my own, I have hereto affixed my signature in the presence of two witnesses.

GEORGE H. VAN NOY.

Witnesses:

WALTON HOOD GRANT,
ESTHER McLACHLAN.
